UNITED STATES PATENT OFFICE.

EMILE LOUIS ALFRED SAVY, OF PARIS, FRANCE.

SANDWICH-MACHINE.

1,160,532.

Specification of Letters Patent. Patented Nov. 16, 1915.

Application filed March 4, 1912. Serial No. 681,452.

To all whom it may concern:

Be it known that I, EMILE LOUIS ALFRED SAVY, a citizen of the Republic of France, residing at Paris, in the Department of Seine, France, have invented new and useful Improvements in Sandwich-Machines, of which the following is a specification.

This invention relates to a machine for making sandwiches, preferably those kind of sandwiches in which cream (plastic confection) is inserted between two layers of thin, flat cake.

The machine is designed and arranged to form these sandwiches in an automatic and efficient manner.

The object of the invention is to provide a machine of the class described which will operate in a most efficient manner for the purpose desired.

20 The specific objects of the invention will appear in the detailed description and annexed claims.

In the drawings forming part of this application, Figure 1 is a side view of the 25 assembled machine showing the general arrangement of the more important parts. Fig. 1^a is a detailed view showing the arrangement by which the lifting table is operated, and the mechanism by which the 30 cream receptacle is operated. Fig. 2 is an end view of the apparatus adjacent the cream receptacle. Fig. 3 is a plan view of the frame with the sprocket wheels and lifting table assembled thereon. Fig. 4 is an 35 enlarged, detailed view of the cream receptacle. Fig. 5 is an enlarged detailed view of the means for feeding the covering cake onto the cream. Fig. 6 is a detailed view of the spring-pressed plate carried by the oscillating table. Fig. 7 is a detailed, cross sectional view of the plate over which the 40 cream receptacle moves, and the opening in said plate through which the cream is fed to the cake. Fig. 8 is another cross sectional view of the same part looking at 45 right angles to the former figure. Fig. 9 is a view of certain gearing. Fig. 10 is a detailed view of the cam used to raise the table.

50 The general operation of the machine is as follows: An endless belt carries containers for each sandwich which is to be made. A base cake is first fed to each container; the cream is then fed onto the base cake and then the covering cake is fed onto the cream, after which the completed sand-

wich is pressed together and then it leaves the apparatus. The covering cake may be omitted, if desired. All of this operation is performed automatically with the specific 60 mechanism to be described.

The frame 1 has mounted therein a main driving shaft *a* which is driven from any suitable source of power. At each end of the frame, sprocket wheels 26 (see Fig. 3) 65 are suitably mounted which carry endless chains that carry receptacles 21 for the sandwiches to be made (see Fig. 5). These receptacles extend one after another around the chains, as disclosed in said figures. The 70 upper travel of the belt *h* is rendered level and the chain prevented from sagging by the horizontal support 28.

The sprocket wheels are operated from the shaft *a* as follows: Mounted on the 75 shaft *a* is a crank-arm *b* which has a link connection with the arm *c* pivoted on the main frame at *z*. At the upper end of this arm another link connection connects the arm *e*, pivoted on the shaft *g*, which contains at its upper end a pawl operating on a ratchet *f*, which ratchet is fast on the shaft *g*. As clearly disclosed in Fig. 1, this link motion is shown capable of considerable adjustment. By means of the slot in the arm 80 *e* and the cross-head *d*, together with the adjusting holes shown in the lever *c* it is possible to get a very wide range of adjustment and thus control the movement transmitted to the shaft *g* from the shaft *a* by 85 90 means of the link motion and ratchet mechanism described. It is seen from this mechanism that the chain will have an intermittent motion in one direction, as the shaft *a* rotates continuously. 95

Mounted above the chain, on the frame 1, is the cream receptacle *m* which is arranged to reciprocate lengthwise of the apparatus in a manner now to be described.

Figs. 4 and 2 best disclose the specific 100 mounting of the cream receptacle. The side guards 11 keep the receptacle from any movement transverse of the machine. A plate 5 is rigidly mounted under the cream receptacle on which the receptacle bears. 105 This plate 5 has openings 14 (see Fig. 8) therein through which the cream is fed to the cakes. The openings 14 are arranged in a series which is transverse to the machine. In the present case, there are ten openings, as 110 seen in Fig. 2, but of course any number desired may be used. The outlet of the

cream receptacle is open all the time, and at each end thereof there is a spring-pressed plate 8 with means to increase the pressure of said spring 3, as disclosed in Fig. 4. The 5 plate 5 is highly polished and allows the cream receptacle to slide thereover. The spring-pressed plates 8 prevent any cream from leaving the receptacle as it slides on the plate 5, except when the receptacle passes over the openings 14. This receptacle is operated as follows from the shaft *a*: A mutilated gear and mechanism similar to a Geneva stop motion, as shown in Figs. 1^a and 9, transmits motion from the shaft *a* to the 10 shaft *j*. When the shaft *a* turns a complete revolution, the shaft *j* turns a half revolution, as is clear from said Fig. 9, and the shaft *a* having the mutilated gear *n*, will be turning for a considerable period, while 15 the shaft *j* is at rest, which is also clear from said figure. Mounted on the shaft *j* is a crank-arm *k* and a link connection therefrom to an oscillating lever *i* which is mounted on the main frame intermediate of 20 its ends, as shown in Fig. 1. As this lever *i* oscillates it moves the cream receptacle *m* through the link connection *l*, which is pivoted to *m* at 10. The movement of the receptacle *m* will be as follows as the shaft *a* 25 rotates continuously: It will first move to the left (see Fig. 1) then there will be a dwell, after which it will move to the right, and so on continuously. This will be clear from an examination of Fig. 9. Thus a complete revolution of the shaft *a* moves the receptacle *m* in one direction, and the next complete revolution of the shaft *a* moves it in the opposite direction. Whenever the receptacle *m* slides over the openings 14, 30 cream is fed therethrough to the cakes, which are presented under the opening as follows: Whenever the chain moves forward in its intermittent movement, one of the receptacles 21 moves past the bottom of the 35 cake-feeding device *y* (see Fig. 1) and a cake 23 (see Fig. 5) falls into the recess in the receptacle. The receptacle then carries this cake along with the chain until at one of the dwells in the chain's operation, a table *r* 40 carrying the plates 7 (see Fig. 6) is moved upwardly to press the cake carried by the receptacle 21 into registering position with the opening 14. As the cake is carried up into this registering position it overcomes 45 the springs 15, as shown in Fig. 7. Just as the cake is presented in this movement to the underside of the opening 14, the apparatus is so timed that between the movements of the chain the cream receptacle *m* 50 will be moved past the openings 14 and feed cream through said openings to the face of each of the cakes. Then as the chain *k* moves forwardly the table *r* has allowed the receptacle to fall away from registering position with the opening 14, and the springs 55

15 force the cake down with the receptacle in order to avoid any sticking due to the cream. In this cream feeding operation it is necessary to move the table *r* in exactly the right time with respect to the other 76 movements. The table *r* is mounted pivotally and adjustably at the point *s* (see Fig. 1) in the main frame, and raised and lowered by a link connection 4 having a forked end between which the shaft *a* extends. A 75 cam *o* (see Fig. 1^a) is mounted on this shaft *a* and operates on a roller to raise and lower the table *r*. It will be seen from an examination that the cam *o* shown in Fig. 10 will move the table *r* upwardly during one-half 80 of its revolution, while it will not move it at all during the other half. Thus the table *r* practically remains in one position during a half revolution and in its other position during the other half. The cam *o* is so timed 85 that it operates to throw the table *r* up so that the spring-pressed plate 7, fixed to the table can force the receptacle 21 carrying the cake gently into engagement with the opening 14. The cam holds the table in this 90 position during the time in which the cream receptacle *m* is moving past the openings 14. All this operation may be clearly traced out from the drawings which are believed to be accurate in respect to the operation described. 95

As the chains move forward from under the cream receptacle they carry the receptacles 21 with the cakes and the layer of cream under a second cake feeding mechanism *x* which is best shown in Fig. 5. It will be seen that there is a connection between the shaft *j* and this second cake-feeding mechanism by means of the chain *t*. Whenever the chain *j* rotates, the shaft *u* of the feeding mechanism likewise rotates through the chain, as seen in Fig. 1. The cakes are fed from the second feed device as follows,—see Fig. 5:—As the shaft *u* rotates 100 (and by intermeshing gears not shown rotates the shaft *v*), the cams 18 first oscillate the pivotally mounted holding arm 16 against the holding spring 13, which allows the one cake held by the holding arm 16 to drop directly onto the cream held by the 105 cake in the receptacle 21. It should be noticed that the holding members 17, which are pivotally mounted and spring-pressed into place, support the entire column of 110 cakes in the feeding device *x*, except the very lowest cake, which is held by the member 16. As the shafts *u* and *v* rotate, the cams will cause the lower cakes to first fall and will then allow the member 16 to spring 115 back into place. (The movements of the 120 cams 18 are counter clockwise.) The movement of the arms 17 then will release the whole column of cakes which fall onto the lower arm members 16, after which the members 17 spring back to their normal po- 125 130

sition and hold all the cakes in the column, except the lowermost one. The sandwich has now been completed, except for one operation which is as follows: The transverse bar 20 (see Fig. 5) is mounted over the travel of the belt immediately beyond the second cake-feeding device. The table *r* has a second spring-pressed plate 7 mounted thereon which, when raised by the movement of the table, will push the receptacle carrying the completed sandwich against the plate 20, as is clear from an examination of Fig. 5. The mechanism is so timed that this last operation takes place at the same time that the table *r* is raised to place a following series of cakes in position for the cream to be fed thereon. This operation presses the cakes and cream gently together and makes a firmly fixed sandwich. The chain then continuing to feed, allows the cakes to drop out of the receptacle 21, as the chain turns around the left-hand sprocket-wheel in Fig. 5, or the cakes may then be removed in any suitable manner. The timing of the operations of machine, such as described, is important. The mechanism is timed preferably to operate as follows: The shaft *a* is constantly driven, the shaft *j* and all the mechanism controlled thereby is operated intermittently and the table *r* is raised and lowered intermittently. Now the proper details of the timing being provided for, the operation is generally as follows: The chain is moved forward one step during which time ten receptacles take cakes from the feeder *y*, none of the other parts operating during this movement. The chain then remains stationary while the ratchet goes back for its next forward driving movement. When the chain is stationary, the cam on *a* first raises ten receptacles so that ten cakes register with the ten openings. The cream receptacle has been moving along the smooth plate 5 while the cakes were being put in place, and now passes rapidly over the openings 14 filling them with cream. The next operation is for the cakes carrying the cream to fall away from the openings. The cam allows this by allowing the table to fall. The chain next moves forward and other cakes start through the machine while the coated cakes pass to the second cake-feeding mechanism, all of the cakes stopping directly under this mechanism to get the cover cake during a dwell in the chain's operation. All the cakes also stop directly under the transverse bar 20 during a dwell while the table *r* is raised and the plate 7 presses the cakes together. It can be seen from the drawing that the shaft *j* and associated mechanism operates only during a dwell in the operation of the chain. The cakes are kept from side movement in their carriers by the series of side guides 27.

While a specific form of applicant's invention has been described, it is to be understood that other forms of the invention from the specific one shown may be easily built by one skilled in the art, and it is therefore desired that all generic features of the invention be included in this or other applications, as pointed out in the annexed claims.

What I claim, is:—

1. In combination, means arranged to feed cakes intermittently, a series of conveying receptacles each arranged to be intermittently and successively moved under said means to receive a cake therefrom during the operation of said means, a cream-feeding means mounted above the path of said conveying receptacles to feed cream to the cakes held by the conveying receptacles, and a second cake-feeding means arranged to feed a second cake over the cream on each of the first cakes fed to the several receptacles, and operating means constructed and arranged to positively move said conveying receptacles into proper registering position to the cake-feeding and cream-feeding means, said second cake-feeding means comprising a guideway for the cakes, a pair of arms arranged to support the bottom cake, a second pair of arms to support the remainder of the cakes, means to move the first pair of arms to drop the bottom cake, and to thereafter return said arms to supporting position and means thereafter to move said second pair of arms to drop the column of cakes on said first pair of arms and to return said arms to supporting position.

2. In combination, a frame, an endless belt carrying a series of transversely arranged cake receptacles each having a pocket arranged to completely support a cake and to retain its side edges in correct alinement, a cake feeder under which the receptacles move and receive cakes, a cream receptacle arranged to feed cream to the cakes in the receptacles, and a second cake-feeder comprising a guide for a column of cakes, a supporting means for the lower cake, a supporting means for the remainder of the column, devices to move said first means to drop the lower cake and thereafter to return said means to supporting position, devices to subsequently move said second means to drop said column upon said first means and thereafter to return said means to supporting position.

3. In a sandwich machine, the combination of an endless carrier having receptacles to receive cakes, means for operating the carrier intermittently, means to feed cakes thereto, a cream feeding device to cover said cake with cream between the intermittent movements of said carrier, means to elevate the cakes and present them to the outlet of the cream feeding device during the operation of the same, a second cake feeding de-

- vice to lay cakes upon the cream on the first mentioned cakes, and a device to press said cakes together to form a fixed sandwich, said device operable by said elevating means 5 to yieldingly press said cakes.
4. In a sandwich machine, the combination of a carrier, means to feed cakes thereto, means to feed cream to said cakes and a second feeding means to feed cakes on top of 10 the cream to form sandwiches, said latter means comprising a guideway arranged to receive a column of cakes, pivoted arms arranged to support the bottom cake of the column, other pivoted arms arranged to support the remainder of the column, means to swing the first-mentioned arms to drop the bottom cake and then the second pair of arms to drop the column upon the first pair of arms together with means to return the 15 first-mentioned pair of arms before the second pair operate and means thereafter to return the second pair of arms, whereby they will support all the cakes, except the lower one of the column.
- 20 5. In a sandwich machine, the combination of a carrier, means to feed cakes thereto, means to feed cream to the cakes thereon, a second cake feeding means to feed cakes on top of the cream to form sandwiches, a 25 plate extending transversely over the carrier, and a pivoted frame having spring-pressed plates with means for raising and lowering the frame whereby the spring-

pressed plates force the cakes from the first mentioned feeding means up to the outlet 35 of the cream-feeding means, and the sandwiches up to engagement with the transversely extending plate to press the assembled cakes and cream together.

6. In a sandwich machine, the combination of a carrier, means to feed cakes thereto, means to feed cream to the cakes thereon and a second cake feeding means to feed cakes on top of the cream to form sandwiches, said latter means comprising a vertical guideway adapted to receive a column of cakes, a pair of pivoted arms arranged to support the bottom cake, a second pair of pivoted arms arranged to support the remaining cakes, two cam shafts, and a driving connection therebetween each having cams arranged when said shafts are rotated to swing the first mentioned pair of arms to drop the bottom cake and then the second pair of arms to drop the column of cakes 50 onto the first pair of arms, together with means for returning said first mentioned pair of arms before the second pair operate, and means thereafter to return the second pair of arms where they will support all the 55 cakes, except the lower one of the column.
